UNITED STATES PATENT OFFICE.

MARTIN L. HARTER, OF CLEVELAND, OHIO.

AUTOMOBILE-COT.

1,262,663.

Specification of Letters Patent. Patented Apr. 16, 1918.

Application filed April 16, 1917. Serial No. 162,470.

To all whom it may concern:

Be it known that I, MARTIN L. HARTER, a citizen of the United States, residing at Cleveland, in the county of Cuyahoga and 5 State of Ohio, have invented certain new and useful Improvements in Automobile-Cots, of which the following is a specification.

This invention relates to cots or folding 10 beds to be used in connection with automobiles of the touring car type. Among the objects of the invention is the provision of a device of this character that is simple, economical, and durable in construction, and 15 that provides a convenient and comfortable bed for tourists who desire to use their automobiles as dormitories at any time. Another object of the invention is to provide a device that can be packed and conveniently 20 stored when not in use as a bed, and that can be easily and quickly secured and adjusted in operative position.

With the above and other apparent objects in view the present invention consists 25 in the construction, arrangement, and combination of the parts hereinafter described and pointed out definitely in the claims, reference being had to the accompanying drawings forming a part of the specification, and 30 in which similar characters of reference designate similar parts.

In the drawings Figure 1 is a side elevation of a touring car with certain parts 35 eliminated or broken, and showing an embodiment of the improvement as connected with the car and in position for occupancy as a bed.

Fig. 2 is a plan view of the device unrolled and detached from the car.

40 Fig. 3 is a fragmentary view showing substantially the position of the device when not in use as a sleeping commodity.

The most popular types of touring cars have a long wheel base and body that provides 45 considerable space between the front and rear seats, making the cars roomy and comfortable. These cars are also usually so designed that the back of the rear seat is somewhat higher than the back of the front 50 seat. These existing conditions make possible and convenient the attachment and adjustment of the improved device to cars of this character.

Referring now to the several figures of 55 the drawing, 1 and 2 represent metal rods of a predetermined length a little less than

the transverse dimension of the interior of the car. These rods form transverse end supports and are spaced and connected by longitudinal side supporting members 3. 60 The members 3 consist of strips of flexible material such as leather or heavy canvas, and combined with the end rod members 1 and 2 form a rectangular frame longitudinally flexible and adapted to be folded or 65 rolled around one of the end rods.

Attached to, and extending between the rods 1 and 2 is a sheet of flexible material 4 preferably canvas or heavy duck which forms the body of the bed. Reinforcement 70 or stay members 5 are provided. These members are in the form of strips of flexible material similar to that of the members 3, they are attached to the members 3 as shown at 3^a and extend transversely under 75 the body 4.

Connected with the end rod 1 are strap members 6 which are adapted to pass over the top of the rear seat back b of the car and are attached to a suitable stationary 80 part of the car structure as shown at c Fig. 1. In the embodiment as illustrated, the members 6 are formed with a wide flat surface 6^a for their bearing on the upholstered top of the seat back b, and are reduced for 85 their buckle and strap attachment.

Strap members 3^b may be independently connected with the rod 2 or they may be formed as shown, by extending the side supporting strips 3, the latter being a preferable 90 construction as it provides a desirable, direct tension adjustment. The members 3^b are provided with hooks 7, or other suitable means adapted for connection with the wind-shield support d of the car. 95

To provide freedom of access when the bed has been adjusted for occupancy, as shown in Fig. 1, the rods 1 and 2 are so spaced that the forward end of the body 4 and the rod 2 are in a vertical plane with 100 the back of the front seat e, or the longitudinal distance between the rods 1 and 2 is approximately equal to the distance between the front and back seat of the automobile. By this arrangement the forward compartment 105 of the car is not obstructed, and the front seat provides means for convenient access to the bed. It also provides unobstructed overhead room so that the car can be operated when the bed is in use, without 110 appreciable inconvenience to the driver who occupies the front seat.

The stay members 5 extend beyond the members 3 on both sides and are provided with hooks 8, or other suitable means for attachment to the bows 7 that support the top or canopy, not shown in the drawing. These attachments increase the stability of the device.

When the device is not in use as a bed, the hooks 7 being detached from the support 4, the members 3^b are folded over the body 4, the terminals of the members 5 carrying the attachments 8 are likewise folded over the said body and the device rolled, the rod 2 providing a core and thereby facilitating the rolling of the device into a compact package, the rod 1 being retained by members 6 forms an anchorage for the roll on top of the back 6 of the rear seat, as shown in Fig. 3. If so desired, light bed 20 coverings or articles of wearing apparel may be inclosed in the roll.

The invention as above described provides an article of utility for automobile tourists, that can be manufactured at small expense, 25 and while the construction as shown and described embodies a simple and serviceable device of the character set forth, it will be understood that the improvement is not confined to this specific construction, as there 30 may be modifications in details of attachments, in material, and in the relative proportions of elements, or other minor changes may be made without departure from the nature of the invention which is limited by 35 the scope of the claims.

What I claim and desire to secure by Letters Patent is.

1. In a folding automobile cot the combination of two transverse rigid supporting 40 members spaced apart a distance approximately equal to the distance from the back of one seat of an automobile to the back of the other seat; two strips of flexible material extending longitudinally and connecting 45 the ends of the transverse members thereby forming a rectangular frame which is flexible longitudinally; a body member of flexible material attached to the transverse members and extending in a transverse plane 50 between the longitudinal strips of said frame; means attached to one of the rigid frame members for connection with the rear of the automobile; and means connected with the opposite rigid frame member 55 for connection with the forward part of the automobile whereby the structure is suspended longitudinally in a transverse plane over the tops of the seats.

2. In a folding automobile cot the combination of two transverse rigid supporting 60 members spaced apart a distance approximately equal to the distance from the back of one seat of an automobile to the back of the other seat; two strips of flexible material 65 extending longitudinally and connect-

ing the ends of the transverse members thereby forming a rectangular frame which is flexible longitudinally; a body member of flexible material attached to the transverse members and extending in a transverse plane between the longitudinal strips of said frame; stay members of flexible material attached to the longitudinal strips and extending transversely beneath the body member; means attached to one of the rigid frame members for connection with the rear of the automobile; and means attached to the opposite rigid frame member for connection with the forward part of the automobile whereby the structure is suspended 70 longitudinally in a transverse plane over the tops of the seats.

3. In a folding automobile cot the combination of two transverse rigid supporting members spaced apart a distance approximately equal to the distance from the back of one seat of an automobile to the back of the other seat; two strips of flexible material extending longitudinally and connecting the ends of the transverse members thereby forming a rectangular frame which is flexible 85 longitudinally; a body member of flexible material attached to the transverse members and extending in a transverse plane between the longitudinal strips of said frame; stay 90 members of flexible material attached to the longitudinal strips and extending transversely beneath the body member; means attached to the stay members for connection with the bow members of the automobile top; 95 means attached to one of the rigid frame members for connection with the rear of the automobile; and means attached to the opposite rigid frame member for connection with the forward part of the automobile whereby 100 the structure is suspended longitudinally in a transverse plane over the tops of the seats.

4. In a folding automobile cot the combination of two transverse rigid supporting members spaced apart a distance approximately equal to the distance from the back of one seat of an automobile to the back of the other seat; two strips of flexible material extending longitudinally and connecting the ends of the transverse members thereby 110 forming a rectangular frame which is flexible longitudinally; a body member of flexible material attached to the transverse members and extending in a transverse plane between the longitudinal strips of said frame; means attached to one of the rigid frame members for connection with the rear of the automobile; 115 extensions of the longitudinal strips extending forward from the opposite rigid frame member; and means attached to said extensions for engagement with the wind shield support whereby the structure is suspended longitudinally in a transverse plane over the tops of the seats.

5. In a folding automobile cot the combi- 120

nation of two rigid transverse supporting members spaced apart a distance approximately equal to the distance from the back of one seat of an automobile to the back of the other seat, one of said rigid members being connected with the top of the rear seat back; two strips of flexible material connecting the ends of the transverse members respectively, and extending forward of the other rigid member; means attached to said

extensions for engagement with the wind shield support; a body member of flexible material attached to the transverse members and extending in a transverse plane between the connecting strips; take-up means provided in the extending members of the connecting strips whereby said strips can be made taut. 15

In testimony whereof I affix my signature.
MARTIN L. HARTER.
